Primary Examiner — David G Muller*Assistant Examiner* — Nathan M Johnston(74) *Attorney, Agent, or Firm* — Spencer Fane LLP;
 Steven J. Laureanti(57) **CLAIM**

The ornamental design for a holder, as shown and described.

DESCRIPTION

FIG. 1 is a perspective view of a holder showing my new design in a retracted position;
 FIG. 2 is a front elevation view thereof;
 FIG. 3 is a rear elevation view thereof;
 FIG. 4 is a right side elevation view thereof;
 FIG. 5 is a left side elevation view thereof;
 FIG. 6 is a top plan view thereof;
 FIG. 7 is a bottom plan view thereof;
 FIG. 8 is another perspective view thereof;
 FIG. 9 is a perspective view thereof in an extended position;
 FIG. 10 is a front elevation view thereof;
 FIG. 11 is a rear elevation view thereof;
 FIG. 12 is a right side elevation view thereof;
 FIG. 13 is a left side elevation view thereof;
 FIG. 14 is a top plan view thereof;
 FIG. 15 is a bottom plan view thereof; and,
 FIG. 16 is another perspective view thereof.
